UNITED STATES PATENT OFFICE

FREDERICK H. KUNKEL, OF MILWAUKEE, WISCONSIN, ASSIGNOR TO GEUDER, PAESCHKE & FREY COMPANY, OF MILWAUKEE, WISCONSIN, A CORPORATION OF WISCONSIN

TOGGLE PRESS GUARD

Application filed May 3, 1929. Serial No. 360,071.

This invention relates to a safety device for use on presses and more particularly to a safety device in the form of a traveling gate operating in synchronism with the mechanism of a toggle punch press, and acting to insure that the person feeding the press removes his hand from beneath the blank holder and punch before the blank holder or punch descends into proximity to the die. 10 One of the principal objects of the present invention is to provide a safety guard or safety device of this character which insures that the feeder removes his hand from beneath the blank holder and punch in ample time to avoid any possibility of his hand being caught and crushed or otherwise injured, the safety device operating in advance of the movement of the blank holder and punch in effecting this purpose. 15

Another object of the invention is to provide a safety device of this character and having these advantages and which is of simple and durable construction, reliable and effective in operation, easy and comparatively inexpensive to manufacture and adapted to be installed on standard presses without modification of the press construction and without interfering with its operation or with the changing of the tools or dies. 25

Other objects and advantages reside in certain novel features of the construction, arrangement and combination of parts which will be hereinafter more fully described and particularly pointed out in the appended 30 claims, reference being had to the accompanying drawings, forming a part of this specification, and in which:

Figure 1 is a view in front elevation showing a conventional type of press equipped 40 with a safety guard embodying the present invention;

Figure 2 is a view in transverse vertical section taken on line 2—2 of Figure 1, parts being shown in elevation for the sake of 45 simplicity in illustration;

Figure 3 is a fragmentary detail view in top plan showing the mounting employed for one of the guide rods for the safety gate and associated parts;

Figure 4 is a fragmentary view in front

elevation showing a portion of one end of the safety gate and the mounting and guiding means therefor;

Figure 5 is an enlarged fragmentary view in elevation showing one of the guides for 55 the gate and associated parts;

Figure 6 is a view in horizontal section on line 6—6 of Figure 5, the cotter pin being removed; and

Figure 7 is a view in vertical section on 60 line 7—7 of Figure 5, the cotter pin being shown in elevation.

Referring to the drawings and more particularly to Figures 1 and 2, a conventional toggle punch press is designated generally 65 at 1 and has the usual frame 2 supporting a die 3. On the upper portion of the frame 2 the conventional toggle mechanism 4 is provided and operates as usual to raise and lower the blank holder 5. The punch 6 is 70 reciprocated within the blank holder in the usual manner. Punch presses of this character are well known and widely used and need no detailed description. For the purposes of the present invention it is sufficient 75 to understand that when the blank holder 5 and punch 6 are elevated the operator places a blank of metal over the die 3 and then the blank holder 5 descends to hold the blank in position and finally the punch travels down 80 through the blank holder and coacts with the die 3 to suitably shape the blank. When the blank has been suitably shaped the blank holder and die are elevated and the operator then removes the properly shaped blank and 85 replaces it with another flat blank. At times the operator does not remove his hand in time to prevent its being caught by the blank holder or punch and as a result the hand is crushed. 90

In carrying out the present invention a pair of fixed guide rods 10 are provided, there being one guide rod at each side of the press. Each guide rod has its lower end secured by nuts 11 to a bracket 12, the bracket 12 being fastened to the frame 2 by one of the studs 13 that secures the frame to its base. The upper end of each guide rod passes through an apertured lug 14 provided on an angle bracket 15 secured to the 100

frame of the press by a stud bolt 16. A nut 17 is threaded on the upper end of each guide rod and engages the lug 14 of its bracket.

A safety gate 20 is provided and has a substantially rectangular frame 21 to which a body of wire mesh fabric 22 is secured. Sliding guides, designated generally at 25, are provided for mounting the gate on the guide rods 10 for vertical sliding movement.

10 Preferably, there are four such guides 25, two at each end of the gate. The guides 25 are all of identical construction and each consists of a pair of plates 26 and 27 hingedly connected at one end as at 28. Curved portions 29 on the plates 26 and 27 coact when the plates are brought together to provide a sleeve-like guide which slidably embraces the guide rod 10. The ends of the plates 26 and 27 remote from the hinge 28 are also 15 provided with complementary curved portions 30 which coact to provide a clamp for securing the guide to the adjacent end rail 20' of the frame 21 of the sliding gate. The curved portions 30 have corrugations or 20 crimps 31 therein and are appropriately slotted as at 32 so that these curved portions 30 not only clamp the end rails of the gate but embrace and snugly fit the strands of the 25 wire fabric and gate. One of the plates of 30 each guide, preferably the plate 27, is welded to the gate. For the purpose of releasably securing the plates 26 and 27 together whereby the guide portions 29 constitute a sleeve-like guide slidably embracing their guide 35 rod 10 and the clamping portions 30 are rigidly interconnected with the frame of the gate, the plate 26 has apertured lugs 33 struck therefrom and the plate 27 has slots 34 formed therein through which the lugs 40 33 project when the plates 26 and 27 are brought together. A cotter pin 35 is then inserted through the apertures of the lug 37, as shown in Figures 5 and 7, thereby holding the plates 26 and 27 together.

45 The weight of the gate 20 biases it to move downwardly along the guide rods 10 to the position shown in Figure 1 and if the weight of the frame and wire mesh of the gate is not sufficient for this purpose an additional 50 weight 40 may be secured to the lower rail of the frame. For the purpose of lifting the gate up and controlling the lowering movement thereof, crank arms 41 are secured as by stud bolts 42 to the upper arms of the 55 toggle mechanism 4 that operates the blank holder 5. The outer ends of these arms 41 project beyond the arms 4' of the toggle mechanism and are bent over as shown in Figure 1 to aline their outer ends with the 60 upper sliding guides of the gate. Flexible connections such as chains 43 are provided and each has one end connected to the outer end of an arm 41 and its other end detachably connected to the overlying upper sliding 65 guide 25. The detachable connection be-

tween the lower end of the flexible element 43 and its guide 25 may consist merely of a hook 44 carried by the lower end of the flexible element 43 and engaging in one of a series of openings 45 provided in the guides 25. Intermediate its ends each flexible element 43 is trained over a guide pulley 46 which is rotatably supported as at 47 on the bracket 15.

70 In operation, when the blank holder 5 and punch 6 are in raised position the gate 20 is also in raised position because the arms 41 are then in the dotted line position shown in Figure 2. The operator then puts a blank onto the die 3 beneath the blank holder and punch and if the machine is running then the blank holder and punch descend, but the gate also descends in advance of the blank holder and punch because of the additional throw of the crank arms 41. Thus, if the 75 operator were to be slow in removing his hand from beneath the blank holder and punch it would be struck by the gate 20 which would warn him and tend to displace his hand from beneath the blank holder and punch. When the blank holder and punch are raised the 80 gate 20 is also raised due to the upward movement of the crank arms 41.

85 The sliding guides 25 which are provided serve not only to constrain the gate 20 to vertical sliding movement but also to permit the gate to be swung around to one side of the press to facilitate tool setting. To swing the gate in the manner described the cotter pin 35 associated with the guides at one side 90 of the gate is removed from its lugs 33. Loss of the cotter pin is prevented by virtue of the provision of chains 49 which connect these cotter pins to the wire mesh body of the gate. With one of the cotter pins 35 removed, the 95 plates 26 of the guides at one side may be swung about their hinges 28 thereby releasing the movable guides from the guide rod 10 at one side of the press. When the guides 100 at one side are disengaged from their fixed guide rod 10, they are supported on the gate due to the welding of the plates 27 to the gate. Prior to this the chains 43 are disconnected from the upper guides 25. When the gate is thus disconnected from the flexible elements 43 and from one of the guide rods 10 it is supported in elevated position 105 on the other guide rod by means of a cotter pin 50 also carried on the gate by means of a chain 51 and insertible through a transverse opening provided in the guide rod. The gate is thus supported elevated when it is swung out of the way because in its lowermost position it might interfere with convenient access to the tools.

110 The invention claimed is:

1. A safety device for use on punch presses of the type including a die, a blank holder and a punch and a toggle operating mechanism therefor and comprising a traveling gate dis-

posed in front of the die, blank holder and punch, means for constraining the gate to vertical sliding movement, means actuated by the operating mechanism of the press for 5 constraining the gate to movement downwardly in advance of the blank holder and comprising crank arms connected to the arms of the toggle mechanism of the press and having a greater throw than the arms of the 10 toggle to which they are connected, and flexible connections between said crank arm and said sliding gate.

2. A safety device for use on punch presses and comprising vertical guide rods supported 15 upon the press, a gate, movable guides secured to the gate and slidably embracing the guide rods, and means connected to said movable guide for raising the gate up and down as the press is operated, at least certain of 20 said guides comprising a pair of plates hinged together and having coacting portions providing a sleeve-like guide adapted to slidably embrace the guide rod, said plates also having portions adapted to be secured to the 25 gate.

3. A safety device of the character described including fixed vertical guides, a gate, and sliding guides fixed to the gate and slidably embracing said fixed guides, at least 30 certain of said sliding guides comprising a pair of plates hingedly connected at one end and having cooperable curved portions adapted to constitute a sleeve-like guide structure which slidably embraces the associated 35 fixed guide, said plates also having cooperating curved portions adapted to be secured to the gate, and means for releasably securing the plates together and means for moving the gate.

40 4. A safety device of the character described including fixed vertical guides, a gate, and sliding guides fixed to the gate and slidably embracing said fixed guides, at least certain of said sliding guides comprising a pair 45 of plates hingedly connected at one end and having cooperable curved portions adapted to constitute a sleeve-like guide structure which slidably embraces the associated fixed guide, said plates also having cooperating curved 50 portions adapted to be secured to the gate, means for releasably securing the plates together, means for moving the gate, and means for supporting the gate in elevated position on one of the fixed guides when it is released 55 from the other guide whereby to facilitate tool setting and the like.

5. A safety device for use on punch presses and including fixed guides, a traveling gate, sliding guides fixed to the gate and slidably 60 embracing said fixed guides, means provided for synchronized movement of the gate as the press is operated, at least certain of said sliding guides being made up of releasably connected elements which embrace their associated fixed guide whereby they may be disengaged

from their fixed guide, and means for supporting the gate in elevated position when certain of the sliding guides are disconnected from their fixed guide.

6. A safety device for use on punch presses and including fixed guides, a traveling gate, sliding guides fixed to the gate and slidably embracing said fixed guides, means for constraining the gate to up and down as the press is operated, at least certain of said sliding guides being made up of releasably connected elements which embrace their associated fixed guide whereby they may be disengaged from their fixed guide. 70

7. A safety device for use on punch presses and comprising a traveling gate disposed in front of the press, means for constraining the gate to vertical sliding movement, means providing movement of the gate downwardly in advance of the operation of the press, and releasable means for supporting the gate in elevated position. 80

In witness whereof, I hereto affix my signature.
